AUTOMATIC OIL REGULATOR

Henry M. Mitchell, Pink Hill, N.C.

Application October 28, 1947, Serial No. 782,620

3 Claims. (Cl. 236—94)

1

This invention relates to automatic oil regulators.

It is an object of the present invention to provide an automatic oil regulator which is particularly adapted for use with oil burners which are used for curing tobacco in tobacco houses or barns which will cut off the oil and give a signal if the temperature goes above a predetermined point in the barn and wherein regardless of the change in temperature on the outside of the barn, the temperature will not rise in the barn when the leaf dries out and by the use of the regulator the temperature within the barn can be easily lowered as the tobacco dries out and a regulation must be made to keep the burner and the temperature from getting too high again and wherein the oil flow to the burners can be arranged to give a heat from the burners of from 80 degrees Fahrenheit to 210 degrees Fahrenheit with only a 2 degree variation permitted when a setting has been effected.

Other objects of the present invention are to provide a regulator which does not need electric current to operate the same, which is of simple construction, which will remain cut off until again set by the operator, inexpensive to manufacture and efficient in operation.

For other objects and for a better understanding of the invention, reference may be had to the following detailed description taken in connection with the accompanying drawing, in which

Fig. 1 is a top plan view of the burner control embodying the features of the present invention.

Fig. 2 is a front elevational view of the control box.

Fig. 3 is a sectional view, in elevation, taken on line 3—3 of Fig. 1.

Fig. 4 is a sectional view, in elevation, taken on line 4—4 of Fig. 2.

Fig. 5 is a perspective view of the member within the control box for supporting the adjusting screws.

Fig. 6 is a side elevational view of the indicating arm.

Fig. 7 is a front elevational view of the indicating arm.

Referring now to the figures, 10 represents the control box which is disposed on the barn wall by fastening screws 12 extending through lugs 13 and fixed to the barn wall. The control box is disposed at a higher level than the oil valve 14 which controls the flow of oil from a storage tank 15 and to a burner not shown. The oil valve has a pipe 16 extending from the tank 15 to its

2

casing and another pipe 17 which can extend to a burner. Within the oil valve is a throttle valve element 18 normally held in a lifted position by a spring 19 reacting between a head 21 on the valve element and a fitting 22 for connecting the oil valve 14 to the control box 10.

On the top of the control box 10 is a casing 25 which contains a bellows 26 with an adjustable projection 27 which extends downwardly through an opening in the top of the box. This bellows 26 is connected by a tube 28 with a thermal responsive device 31 supported on a bracket 32 connected to wall 33 of the barn and on the interior thereof to be responsive to the inside temperature.

Beneath the projection of the bellows is a bell crank member for adjusting screw support 34 which is pivoted on a pin 35 carried on a bracket 36 on the interior of the box. This member 34 contains adjustable screws 37 adapted to engage with the head 21 of the valve element 18. The projection 27 of the bellows is adjustable within the bellows and is adapted to enter a depression 370 on the member 34 to force the member so that the adjusting screws 37 will be in engagement with the valve element 18 to move it downwardly as the bellows expand to reduce the flow of oil to the burner. The lower end of the valve element has elongated slots 38 and the further 30 the valve 18 is moved downwardly the less oil passes through these slots.

To set the member 34, an adjusting screw 41 is turned by a crank 42. This screw is threaded in an indicating member 43, Figs. 6 and 7, which 35 will be moved along a scale 44, Fig. 2, so that its point 45 will register with any one of a desired 40 temperature reading to which temperature the barn is to be kept. On the depending arm of the bell crank 34 is a projection 45 to which spring 46 is anchored. This spring is connected to the member 43. As the member 43 is adjusted a greater pull will be placed upon the spring 46 and upon the member 43 whereby to elevate the member 34 to a greater extent to reduce the size 45 of the bellows 26.

The temperature can be found to which the scale can be set by allowing the barn to be heated to have a yellowing effect upon the tobacco and then turning the screw 41 until the member 34 50 is brought tight against the projection 27 of the bellows. Thereafter the regulator will keep this same temperature in the barn. To increase the temperature within the barn, the crank will be turned a little at a time until the barn temperature reaches the same as the setting of the

pointer upon the scale 44. Screw 51 in the top of the box 10 serves as a stop to keep the member 34 from rising. This stop 51 is adjustable. A plug 52 can be removed from the box in order to gain access to the adjustable screws 31.

There are two oil valves 14 connected to the box and there is one adjustable screw 31 for each oil valve. Thus the burners can be adjusted so that one can receive more oil than the other.

If the temperature in the building rises, the bellows will force the member 34 down against the action of the spring 46 and will close the valve 18 slightly. As soon as the pressure decreases on the member 34, spring 46 will pull the member up and increase the oil flow whereby to keep a steady temperature in the building at all times.

If the valve element 18 is moved at any time to the full lowered position to cut off the flow of oil or fluid to the burner, a latch 53 will be raised under bell crank arm 54 of the member 34 to make contact with a terminal 55 whereby to close a circuit including a bell 56 and a battery 57 whereby to ring the bell. The member 34 will thus be held in a lowered position by the latch 53. If it is desired that the bell will not be operated a pivot arm 58 is fitted into a notch 59 on a portion of the latch which extends below the bottom of the control box. The regulator must thereafter be reset. A spring 61 is connected to the latch 53 to urge the same toward the end 54 of the member 34. The bell accordingly will give warning when the burners have been turned off.

The member 34 has depending portions 63 serving to support the adjustable screws 31 which extend through holes 64 and 65 of the member, Fig. 5.

While various changes may be made in the detail construction, it shall be understood that such changes shall be within the spirit and scope of the present invention as defined by the appended claims.

I claim:

1. A burner control arrangement comprising a control casing, a valve housing connected to the casing, a valve operable within the valve housing to control the amount of fluid to be delivered to the burner, a member pivotally connected to the casing and including means adapted to engage with the valve element, biasing means

for extending the valve element into engagement with the pivoted member, and a thermal responsive device having portions engageable with the member to urge the member upon the valve element and to cause its actuation within the valve body to control the flow of fluid passing therethrough, and an adjustable screw in the casing and adapted to be turned by hand, a member on the screw having an indicator arm projection through the casing, a scale on the casing by which reading may be made, and a tension spring extending between the pivoted member and the member on the adjustable screw whereby to urge the pivoted member toward the thermal responsive device, and a spring latch adapted to cooperate with the pivoted member to retain the valve in a closed position when the temperature has been increased beyond a predetermined limit, and a signal device responsive to the operation of the latch for giving a signal when the burners have been turned off.

2. A burner control as defined in claim 1 and a pivoted member on the exterior of the casing and adapted to cooperate with said latch to hold the latch so as to be ineffective and thereby to eliminate the signal device.

3. A burner control as defined in claim 1 wherein said pivoted member is in the form of a bell crank having depending portions extending from one of the arms and at the opposite side of the same, and said engaging means for the member comprising an adjusting screw extending between the depending portion and the arm itself, said spring being anchored to the other arm of the member.
